FOREIGN PATENT DOCUMENTS

GB 489778 A 8/1938

Primary Examiner — Michael A. Pratt*Assistant Examiner* — Wendy L Arminio(74) *Attorney, Agent, or Firm* — Armstrong Teasdale LLP(57) **CLAIM**

The ornamental design for a container cap, as shown and described.

DESCRIPTION

FIG. 1 is a perspective view of a container cap.

FIG. 2 is a top view of the container cap shown in FIG. 1. FIG. 3 is a front view of the container cap shown in FIG. 1. FIG. 4 is a right side view of the container cap shown in FIG. 1.

FIG. 5 is a left side view of the container cap shown in FIG. 1; and,

FIG. 6 is a rear view of the container cap shown in FIG. 1. FIGS. 1-6 are various views of a container cap in accordance with the present design. The container cap is adapted to facilitate breaking a seal covering an opening of a container.

1 Claim, 6 Drawing Sheets---
